REEL

Maurice P. Sieger, Pittsburgh, Pa., assignor to
United Engineering & Foundry Company, Pitts-
burgh, Pa., a corporation of Pennsylvania

Application June 12, 1935, Serial No. 26,100

18 Claims. (Cl. 242—72)

This invention relates to drums or reels and more particularly deals with reels adapted to pull and coil wide metal strip under tension.

In the manufacture of metal strip it has long been the practice to pull the strip from the forming rolls under high tension which has resulted in improved physical characteristics of the strip. However, in recent years the demand for and the production of wider and wider strip has been attended with the problem of providing suitable mechanism for pulling and coiling relatively wide strip metal. The mechanism now ordinarily employed for simultaneously coiling and pulling wide strip directly from the mills is an enlargement of the coiling apparatus of known type such as used for coiling strip material under relatively low tension or winding narrower strip at higher tensions.

Since the strip is pulled and coiled under high tension the reel structure is subjected to forces of great magnitude, particularly where wide strip is coiled. This is because the plurality of convolutions of strip wound under tension exert relatively high pressure on the reel due to the fact that each convolution of strip might be said to act as a shrunk-on hoop or cylinder so that when a plurality of convolutions are wound on top of each other the reel proper is subjected to very high radial and circumferential compressive forces. These compressive forces cause each of the reel segments to be forced inwardly of the reel at high pressure. The collapsing mechanism is accordingly subjected to severe stresses, wear and unit surface pressure, and even the shaft supporting the reel segments encounters not only increased torsional forces but large bending stresses, and where the reel and the material coiled are relatively wide the stresses may cause reel failure. Ordinarily it is undesirable to increase the diameter of a reel in proportion to its width increase in adapting the reel to handle wide strip because the coiled material becomes excessively large in overall diameter. Thus the necessity of maintaining wide reel diameters small has added difficulties in reel construction and successful operation.

Moreover in known types of reels when employed for pulling and coiling wide strip under high tension the very material compressive forces on the reel segments so increase the frictional resistance against reel collapse that it is difficult to collapse the reels to remove the coiled material.

It is accordingly the object of the invention to provide an improved collapsible reel which is

adapted to pull and coil particularly wide metal strip or the like under tension with the reel structure being readily collapsible when desired and with the reel being simple, rugged, long-lived, easily operated, and relatively inexpensive in initial and maintenance costs.

Following the teaching of my invention, suitable wide reels can be provided without material increase in diameter if the central shaft supporting the reel segments is directly supported by all of the segments to eliminate bending of the shaft and if frictional resistance against collapse under high coil compressive forces is overcome by employing the forces themselves for this purpose.

Among the best of the known reels is that disclosed and claimed in Talbot Patent No. 1,905,192 and the principles of my invention can be readily applied to the Talbot structure to improve it for wide, high-tension, coiling work. Hence the invention will be particularly described as incorporated with the structure of the Talbot patent.

In the practice of my invention I provide a collapsible strip reel which is adapted for pulling and coiling sheet material under relatively high tension with the reel structure including a central driven shaft having cam surfaces thereon with a radially fixed segment mounted on the shaft and adapted to have limited relative rotary movement on the shaft and with a plurality of radially movable segments completing the contour of the reel. Means are positioned between the radially movable segments and the cam surfaces of the shaft for controlling the radial position of the radially movable segments. The means are positioned to create a torque tending to move the shaft in a relatively rotary direction with respect to the segments to thereby collapse the reel. The torque is substantially equal to or slightly less than the frictional forces resisting relative rotary movement of the shaft and segments. The radially fixed segment of the reel is formed with a bearing surface engaging the central shaft so that the shaft is supported against bending forces applied to it through the means positioning the radially movable segments. Other features of novelty and simplicity of construction will appear more completely as the detailed description of the invention proceeds.

In the drawings, Fig. 1 is a transverse cross-sectional view, taken on line I—I of Fig. 3, and illustrating the principles of the invention applied to a particular reel construction with the reel shown in expanded, coiling position; Fig. 2 is a view similar to Fig. 1 except that the reel parts are illustrated in collapsed position; and Fig. 3

is a longitudinal cross-sectional view through the reel illustrated in Fig. 1 and taken on line III—III thereof.

The embodiment of the invention illustrated in the drawings includes a central shaft 10 driven by any suitable means such as an electric motor (not shown). The shaft or the motor is preferably provided with braking means (not shown) which assists in collapsing the reel as hereafter described. The shaft 10 may be journaled in any suitable manner but is preferably carried in bearings 12 only at one end of the shaft to allow the shaft to overhang and thereby provide for ready removal of the coiled material from the reel. The shaft 10 carries a radially fixed reel segment 14 which is provided with hubs or dead eyes 15 and 16, at the ends of the segment, that surround the shaft and are journaled thereon with bushings 17 and 18. A cap 19 and associated parts are removably secured to the dead eye 16 to cover the unsupported end of the shaft.

The radially fixed segment 14 carries a plurality of radially movable segments 20 and 21 which are pivotally secured to the fixed segment 14 as by pins 22 and 23 carried in axially spaced sockets 24 formed on the ends of the movable segments. The pins 22 and 23 are received in bearing eyes 25 positioned between the sockets 24 and formed on the fixed segment 14. The pins 22 and 23 have a press fit in the sockets 24 and the bearing eyes 25 are provided with bushings 26 to permit radial movement of the movable segments 20 and 21. The sockets 24 and bearing eyes 25 extend in closely alternate position the full length of the reel to provide the greatest possible bearing support for the hinged connection. This is quite important due to the tremendous pressures to which the reel is subjected.

The adjacent ends of the radially movable segments are formed with interfitting rabbeted ends 32 and a bridging plate 34 is secured to the movable segment 20 to span the rabbeted ends. Springs 36, secured at their ends to pins 38 carried in the movable segments 20 and 21, serve to resiliently urge them to the collapsed position shown in Fig. 2.

Means are provided for controlling the radial position of the movable segments 20 and 21 and for effecting collapsing and expanding of the reel. These means comprise, in the form of the invention shown, hardened-surface rollers 40 carried on the roller bearings 42 and mounted on pins 44 secured in flanges 46 formed integrally with the segments 20 and 21 with the rollers 40 being positioned between the flanges 46 as best seen in Fig. 3. The rollers 40 are positioned the full length of the reel so as to reduce concentrated bearing and rolling pressures. The rollers 40 engage with the shaft 10 which is formed with cam surfaces so that relative rotary movement of the shaft and the segments will effect collapsing and expanding movement thereof. The cam surfaces of the shaft 10 are preferably made in the form of removable hardened-metal blocks 50 and 52 carried in appropriate slots in the shaft. The cam blocks are formed with certain portions of their surfaces extending radially beyond other portions so that movement of the shaft and blocks relative to the rollers 40 moves the rollers and their segments 20 and 21 toward and from the shaft 10. In order that the segment 21 will move radially inwardly during the collapsing movement of the reel just prior to the commencement of the radially inward movement of the reel segment 20, which is necessary to permit the col-

lapsing of the reel as shown in Fig. 2, the low portion of cam block 50 is positioned to engage with its associated rollers 40 prior to engagement of the low portion of cam block 52 and its associated rollers 40.

A particularly important feature of the invention is that the engagement between the rollers 40 and the cam blocks 50 and 52 is not on a center line connecting the axis of the shaft 10 and the pins 44. The contact between the cam blocks 50 and the rollers is to one side of the center line so that forces carried between the rollers 40 and the shaft apply torque to the shaft tending to rotate it relative to the segments. This torque results due to forming the cam blocks 52 with curvatures generated from points lying to one side of the axis of the shaft. Thus, as seen in Fig. 1, the most radially extending portion of the cam block 52 is generated from a radius thrown from the off-center point 60. The most radially extending portion of the cam block 50 is generated from a radius thrown from the off-center point 62.

The particular position of the points 60 and 62, and thus the effective torque tending to rotate the shaft 10 relative to the reel segments, is very carefully determined for each particular reel structure so that this torque substantially balances or is slightly less than the frictional resistance of the reel parts against collapse. In this manner a small additional force effects collapse of the reel regardless of the pressure applied to the reel surface from winding strip under high tension thereon. This result occurs due to the fact that the pressure on the reel is a direct factor of the frictional resistance and a direct factor of the torque so that once the proper relation of torque-resistance balancing has been established the same relation will hold regardless of the pressure.

The reel is adapted to receive and clamp on the end of strip to be coiled thereon and mechanism for this purpose includes a plurality of axially spaced bell cranks 70 journaled on a pin 72 secured in axially spaced flanges 74 formed integral with the radially fixed segment 14. The bell cranks 70 carry a clamping plate 76 which is received in a slot 78 formed in the fixed segment 14. The clamping plate 76 has a nose portion 80 which cooperates with an anvil bar 82 secured in the slot 78 so that strip material S positioned in the slot 78 will be clamped between the anvil bar 82 and nose 80 in a kinked position which will prevent its removal from the clamping means when the bell cranks 70 are in clamping position. A flap 84 is pivotally mounted upon a pin 86 carried in the radially fixed reel segment 14 with the flap normally being urged to the full-line position shown in Fig. 2 by means of a spring 88. During the coiling of the strip S the flap 84 is moved by the strip itself down to the full-line position shown in Fig. 1 to complete the reel contour.

The shaft 10 is provided with axially-spaced driving lugs 90 which are received in the angles of the bell cranks 70 and which engage the arms of the bell cranks to clamp or unclamp the strip and to drive the reel in the direction of the arrow during normal coiling. The shaft 10 is also formed with a stop 92 which together with the driving lugs 90 form limits for the relatively rotary movement of the shaft 10 and the reel segments as requisite for collapsing and expanding the reel.

Another important feature of the invention is

the provision of equal and full support for the shaft 10 to avoid bending stresses therein. To this end the segment 14 is provided with a radially inwardly extending portion which is formed with 5 a bearing surface 94, part of which is carried on the flanges 74. Bearing plates 96 are secured to the shaft 10 positioned between the driving lugs 90 and engage with the bearing surface 94. The plates 96 are preferably spaced apart as described 10 but may comprise a single long plate secured to the shaft and notched at one side to fit around the driving lugs 90. With either construction the bearing surface is lubricated as by passage 98. By the constructions just described the shaft 10 15 is given support over its entire length at a point substantially diametrically opposite of the radial forces from the rollers 40 as created by compressive stresses from a plurality of convolutions of strip wound on the reel under high tension. 20 The radially fixed reel segment 14 may have means associated therewith for braking the reel segments or holding them against rotation and for this purpose the dead eye 15 on the fixed segment is illustrated as mounting a brake drum 100 25 which may be used to assist in collapsing the reel if desired or necessary. Thus the drum can be gripped and the drive to the shaft 10 reversed to positively collapse the reel if the case should possibly arise where the momentum collapsing means 30 fails to function or its use is undesirable.

It is believed that the operation of the apparatus will be generally understood from the foregoing description. However, briefly it comprises inserting the end of a metal strip S in the reel slot 35 78 with the reel parts in the collapsed position shown in Fig. 2. The shaft 10 is then driven in the direction shown by the arrow to move the driving lugs 90 into engagement with the bell cranks 70 which clamps the end of the strip S, as 40 shown in Fig. 1, and also then begins to turn the reel segments and coil the strip on the reel. When the shaft 10 is moved relative to the reel segments as just described, the cam blocks 50 and 52 engage with the rollers 40 to move the 45 radially movable reel segments 20 and 21 to the expanded position shown in Fig. 1. Shaft 10 is then continuously driven at the desired speed until the strip is coiled on the reel. The apparatus can be used for coiling at low tension but is 50 particularly adapted to pull and coil the strip under relatively high tension.

When the strip has been completely coiled on the reel, the shaft 10 is braked either by dynamic motor braking or by other suitable means and 55 the momentum of the coil and reel tends to carry the reel segments in relative rotary movement beyond the braked shaft. Inasmuch as the rollers 40 engage with the shaft 10 through the cam blocks 50 and 52 in off-radial direction to establish 60 the torque heretofore described, the momentum of the reel collapses the reel regardless of the high frictional forces set up in the reel due to the considerable pressures effected by the coiled strip. With the reel collapsed the coil can be 65 readily removed and the apparatus is then ready for another coiling operation. The brake 100 on the reel can also be used as an alternative for collapsing if desired.

During coiling under high tension which tends 70 to push the radially movable segments 20 and 21 of the reel inwardly against the shaft 10 with high radial forces, particularly where the reel is relatively wide, the shaft is kept from bending under these forces by provision of the bearing between 75 the fixed segment 14 and shaft 10. When the

forces tending to bend the shaft and carried by the bearing means just described are increased due to the high tension coiling of material on the reel, the torsional forces tending to rotate the shaft and collapse the reel are also simultaneously increased. Thus the relation of torque and frictional resistance is maintained constant regardless of the particular type of strip coiled or the tension at which it is coiled. 5

It will be evident from the foregoing description that an improved reel structure has been provided wherein collapsing of the reel can be readily obtained regardless of the forces on the reel structure due to coiling strip under high tension. The reel structure is adapted to pull 15 and coil strip or the like and specifically wide metal strip under high tension without failure. The structure avoids concentrated unit area pressures and is simple, rugged, easily operated and relatively inexpensive and functions substantially 20 automatically to effect collapsing of the reel after coiling. Although the apparatus has been particularly described for pulling and coiling wide metal strip under high tension it should be appreciated that it is broadly applicable wherever 25 a collapsible drum or reel is desired and that various materials can be wound, wrapped, or placed on the reel with or without tension and with the material and the reel being of substantially any 30 width.

While in accordance with the patent statutes one embodiment of the principles of the invention has been particularly illustrated and described it should be understood that the invention is not limited thereto or thereby but is defined 35 in the appended claims.

I claim:

1. A collapsible reel comprising a shaft, a reel section journaled on the shaft and with bearing support over substantially the full length of the 40 shaft, means for limiting relative, rotary movement of the section on the shaft, a pair of other reel sections each pivotally secured to the first-named section and together with the first-named section defining the reel circumference, a sliding 45 rabbeted joint at the adjacent edges of the other reel sections, a bridging plate secured to one of the other reel sections and spanning the rabbeted joint, spring means connecting the other reel sections and tending to collapse the reel, 50 rollers journaled on the unpivoted ends of the other reel sections substantially the full length thereof, cams on the shaft with the rollers being urged against the cams by the spring means, said cams having a contour such that relative, rotary 55 movement of the shaft and the first-named section effects radial movement of the rollers and the collapse or the expansion of the reel, said rollers contacting with the cams at points to one side of lines joining the axis of the rollers and the shaft so that external pressure on the reel tends to turn the shaft relative to the reel sections to collapse the reel, said shaft-rotating tendency being substantially counterbalanced by the 60 friction in the bearings supporting the first-named reel section on the shaft, and means controlled by relative, rotary movement of the shaft and reel sections for clamping on the end of material to be wound on the reel. 65

2. A collapsible reel comprising a shaft, a reel section journaled on the shaft, means for limiting relative, rotary movement of the section on the shaft, a pair of other reel sections each pivotally secured to the first-named section and together 70 75

with the first-named section defining the reel circumference, spring means connecting the other reel sections and tending to collapse the reel, rollers journaled on the unpivoted ends of the 5 other reel sections, cams on the shaft with the rollers being urged against the cams by the spring means, said cams having a contour such that relative, rotary movement of the shaft and the first-named section effects radial movement of the 10 rollers and the collapse or the expansion of the reel, said rollers contacting with the cams at an angle so that external pressure on the reel tends to turn the shaft relative to the reel sections to collapse the reel, said shaft-rotating tendency being substantially sufficient to counter-balance the 15 friction in the bearings supporting the first-named reel section on the shaft.

3. A collapsible reel comprising a rotatable drum including radially fixed and radially movable sections, spring means connecting the movable reel sections and tending to collapse the reel, rollers journaled on the movable reel sections, a shaft extending through the rotatable drum, cams on the shaft with the rollers being urged 20 against the cams by the spring means, said cams having a contour such that relative, rotary movement of the shaft and the drum effects radial movement of the rollers and the collapse or the 25 expansion of the reel, said rollers contacting with the cams with a non-radial component so that external pressure on the reel tends to turn the shaft relative to the drum to collapse the reel, said shaft-rotating tendency being substantially 30 counterbalanced by the friction in the bearings 35 between the reel sections and the shaft.

4. A collapsible reel comprising a shaft, a reel section journaled on the shaft and with bearing support over substantially the full length of the shaft, a pair of other reel sections each pivotally 40 secured to the first-named section and together with the first-named section defining the reel circumference, a sliding rabbeted joint at the adjacent edges of the other reel sections, a bridging plate secured to one of the other reel sections 45 and spanning the rabbeted joint, spring means connecting the other reel sections and tending to collapse the reel, rollers journaled on the unpivoted ends of the other reel sections, cams on the shaft with the rollers being urged against the 50 cams by the spring means, said cams having a contour such that relative, rotary movement of the shaft and the first-named section effects radial movement of the rollers and the collapse or the expansion of the reel, and means controlled 55 by relative, rotary movement of the shaft and reel sections for clamping on the end of material to be wound on the reel.

5. A collapsible reel comprising a shaft, a reel section journaled on the shaft and with bearing 60 support over substantially the full length of the shaft, a pair of other reel sections each pivotally secured to the first-named section, a sliding rabbeted joint at the adjacent edges of the other reel sections, a bridging plate secured to one of the other reel sections 65 and spanning the rabbeted joint, spring means connecting the other reel sections and tending to collapse the reel, rollers journaled on the unpivoted ends of the other reel sections substantially over the full length thereof, 70 cams on the shaft with the rollers being urged against the cams by the spring means, said cams having a contour such that relative, rotary movement of the shaft and the first-named section effects radial movement of the rollers and the collapse or the expansion of the reel.

6. In combination in a collapsible drum, a radially fixed segment, radially movable segments pivotally secured to the fixed segment, a shaft journaled in the radially fixed segment, cam means positioned between the shaft and the movable 5 ends of the movable segments so that relative, rotary movement of the shaft and the segments effects expansion and collapse of the drum, the contact of the cam means between the shaft and the segments being at an angle to the radial so 10 that pressure on the outside of the drum tends to turn the shaft relative to the segments to collapse the drum, the angle being such at the engaging cam means that the forces tending to collapse the drum substantially overcome the frictional forces resisting collapse whereby the drum can be collapsed with a minimum of additional 15 application of force.

7. In combination in a collapsible drum, a shaft, a radially fixed segment associated with the shaft 20 for relatively rotary movement therewith, radially movable segments pivotally secured to the fixed segment, means positioned between the shaft and the movable ends of the movable segments so that relative, rotary movement of the shaft and the 25 segments will effect expansion and collapse of the drum, the contact of the means between the shaft and the segments being at an angle to the radial so that pressure on the outside of the drum tends to turn the shaft relative to the segments to collapse the drum, the angle being such that the forces tending to collapse the drum substantially 30 overcome the frictional forces resisting collapse whereby the drum can be collapsed with a minimum of additional application of force. 35

8. A collapsible strip reel adapted for pulling and coiling strip and the like under relatively high tension comprising a central driven shaft having cams thereon, a radially fixed segment mounted on the shaft and adapted to have limited 40 relatively rotary movement on the shaft, a plurality of radially movable segments completing the contour of the reel, means positioned between the radially movable segments and the cams on the shaft and in engagement with the cams for controlling the radial position of the radially movable segments, said means positioned to effect a torque tending to move the shaft in a relatively rotary direction with respect to the segments to collapse the reel when strip is coiled under tension on the 45 reel, the torque being substantially equal to the frictional forces resisting relative, rotary movement of the shaft and segments.

9. A collapsible strip reel adapted for pulling and coiling strip or like material under relatively high tension comprising a radially fixed segment, a plurality of radially movable segments completing the contour of the reel, relatively rotatable means carried by the segments, means positioned between the radially movable segments and the 60 relatively rotary means for controlling the radial position of the radially movable segments, said means, when the reel is subjected to heavy compressive forces by coiling strip thereon, being positioned to effect a torque tending to move the relatively rotary means in a relatively rotary direction with respect to the segments to collapse the reel, the torque being substantially equal to the forces 65 resisting relative, rotary movement of the rotary means and the reel segments.

10. A collapsible strip reel adapted for pulling and coiling strip under relatively high tension comprising a central driven shaft having cam surfaces thereon, a radially fixed segment mounted on the shaft and adapted to have lim- 70 75

- ited relatively rotary movement on the shaft, a plurality of radially movable segments completing the contour of the reel, means positioned between the radially movable segments and the 5 cam surfaces of the shaft and in engagement with the cam surfaces for controlling the radial position of the radially movable segments, said means positioned to effect a non-radial movement of the engaging surfaces in the collapse 10 of the reel, the means positioning the radially movable segments being relatively circumferentially spaced from the most radially extending areas of their respective contacting cam surfaces so that certain of the movable segments move 15 radially inwardly before the others during collapsing of the reel.
11. A collapsible reel for pulling and coiling strip or the like under relatively high tension including a shaft, a plurality of reel segments 20 mounted on the shaft and adapted to have relative, rotary movement on the shaft, means associated with the shaft for moving and holding certain of the segments radially to expand and collapse the reel, and bearing means mounted 25 on a non-radially movable segment and supporting the shaft against forces applied to it through the means for radially moving certain of the segments.
12. An automatically collapsible reel for pulling and coiling strip under tension including a 30 rotatable member, a radially fixed reel section and a radially movable reel section journaled for slight relatively rotary movement on the rotatable member, a cam surface associated with the 35 rotatable member, roller means carried by the radially movable reel section and engaging with the cam surface in a non-radial direction so that when strip is coiled on the reel under tension a turning force on the rotatable member results 40 which is substantially equal to the friction against turning, bearing means in addition to those journaling the radially fixed section and positioned between and abutting against the radially fixed section and the rotatable member 45 for substantially the entire length of the section, and means for releasably locking the end of a strip in one of the reel sections.
13. A collapsible reel for pulling and coiling strip or the like under tension including a radially fixed reel section and a radially movable reel section, a member journaled for relatively rotary 50 movement on the sections, a cam surface associated with the member, means carried by the radially movable reel section and engaging with the cam surface in a non-radial direction, and bearing means in addition to those journaling the member and positioned between and abutting against the radially fixed section and the member for substantially the entire length of the section.
- 60 14. A collapsible reel for pulling and coiling
- strip under tension including a rotatable member, a radially fixed reel section and a radially movable reel section journaled for limited relatively rotary movement on the rotatable member, a cam surface associated with the rotatable member, means carried by the radially movable reel section and engaging with the cam surface so that when strip is coiled on the reel a turning force on the rotatable member is effected tending to turn the rotatable member to permit radially inward movement of the radially movable section, and bearing means in addition to those journaling the radially fixed section and positioned between and abutting against the radially fixed section and the rotatable member for substantially the entire length of the section. 5
15. A collapsible reel for pulling and coiling relatively wide strip under tension including a rotatable member, a radially fixed reel section and a radially movable reel section journaled for 20 limited relatively rotary movement on the rotatable member, a cam surface associated with the rotatable member, and means carried by the radially movable reel section and engaging with the cam surface in such position that compressive forces on the reel effect a turning force on the rotatable member tending to turn the rotatable member to permit radially inward movement of the radially movable section. 25
16. An automatically collapsible reel for pulling and coiling strip under tension including a 30 rotatable member, a radially fixed reel section and a radially movable reel section journaled for slight relatively rotary movement on the rotatable member, and bearing means in addition to 35 those journaling the radially fixed section and positioned between and abutting against the radially fixed section and the rotatable member for substantially the entire length of the section.
17. A reel comprising a central shaft, a hub 40 mounted for relative rotation at each end of said shaft, a fixed segment supported by said hubs, a collapsible segment pivoted at one end to said fixed segment, said shaft being disposed upon relative movement to engage and expand the free 45 end of said collapsible segment, means interposed between the fixed segment and the shaft intermediate said hubs to support said shaft against deflection caused by the force required to maintain said free end in its expanded position. 50
18. A reel comprising a central shaft, a hub mounted for relative rotation at each end of said shaft, a fixed segment supported by said hubs, a collapsible segment pivoted to said fixed 55 segment, said shaft being disposed upon relative movement to engage and expand the free end of said collapsible segment, said shaft being supported intermediate said hubs by said fixed segment. 60

MAURICE P. SIEGER.
